CHILD'S VELOCIPED

Laurie Jay Campbell and Raymond John Lohr, Erie, Pa.,
assignors to Louis Marx & Co., Inc.

Filed Aug. 15, 1972, Ser. No. 280,916

Term of patent 14 years

Int. Cl. D21—01

U.S. Cl. D34—15 AL

FIG. 1

FIG. 3

FIG. 1 is a top, rear perspective view of a child's velocipede showing our new design;

FIG. 2 is a front elevational view thereof; and

FIG. 3 is a side elevational view thereof.

We claim:

The ornamental design for a child's velocipede, as shown.
